PRESSURE-STARTING VAPOR HEATING SYSTEM

Paul B. Parks, Oak Park, Ill., assignor to Vapor Car Heating Company, Inc., Chicago, Ill., a corporation of New York

Application May 17, 1940, Serial No. 335,721

10 Claims. (Cl. 237—6)

This invention relates to a pressure-starting vapor heating system, more particularly a steam heating system designed to rapidly fill the radiator with steam under a predetermined low but super-atmospheric pressure when the radiator inlet valve is first opened, and subsequently to keep the radiator filled with steam at substantially atmospheric pressure until the valve is again closed.

This system of heating is basically a reserve volume system designed to overcome unequal heat distribution over the surface of a steam radiator in air-conditioning apparatus where the radiator is positioned in the path of an air stream and it is essential that all parts of the radiator be equally heated at any one time to insure an equal distribution of heat to all parts of the air stream flowing thereover. This system is especially designed for use in a system where fast acting or "cycling" thermostats are used, that is artificial heat is applied to the thermostat so that the on and off cycles of the valve will be frequent. Due to the fact that, in railway cars especially, a very rapid action of the thermostat is necessary to prevent high and low swing in the temperatures, the radiators do not in many cases receive steam fast enough at the start of the "on" cycle and only a portion of the radiator is filled with steam. This causes stratification or ununiform distribution of the heated air.

With this new system of heating a radiator, steam is stored up in the feed conduit connections to the radiator (which conduit may for this reason have an enlarged capacity) at a predetermined pressure and volume to assure a complete filling of the radiator with dry steam the instant the radiator valve opens. As soon as this initial filling is accomplished, the system may return to the ordinary "vapor system" operation governed by the steam and condensate returning to the vapor regulator from the radiator. The principal distinguishing feature of this new system over the ordinary vapor heating system is that the radiator is filled immediately with steam as soon as the radiator inlet valve is opened.

The principal object of this invention is to provide a new pressure-starting vapor heating system of the type briefly described hereinabove and disclosed more in detail in the specifications which follow.

Another object is to provide means for maintaining and storing a quantity of steam under a low but super-atmospheric pressure, sufficient

to quickly fill a radiator when the inlet valve is opened.

Another object is to provide means, cooperating with the steam-storage means, for keeping the radiator filled with steam at atmospheric pressure after the radiator is initially filled and until the valve is again closed.

Another object is to provide improved means for automatically reducing the pressure of steam supplied to a radiator from a high pressure source so that this steam will be initially introduced into the radiator in a sufficient volume and under a sufficient pressure to quickly fill the radiator, and the steam supply in the radiator will be subsequently replenished under a lower pressure and at a rate just sufficient to keep the radiator filled with steam.

Other objects and advantages of this invention will be more apparent from the following detailed description of one approved apparatus-combination constructed, assembled and operating according to the principles of this invention.

In the accompanying drawings:

Fig. 1 is a diagrammatic elevation of one end portion of a railway car equipped with the improved heating system.

Fig. 2 is a wiring diagram for the thermostatic control mechanism of the radiator inlet valve.

Fig. 3 is an enlarged central vertical section through the vapor-regulator, this view being taken substantially on the line 3—3 of Fig. 1.

Fig. 4 is an enlarged central vertical section through the improved radiator-inlet valve.

Fig. 5 is a central vertical section through the water-seal at the lower end of the feed-pipe connection, this view being taken substantially on the line 5—5 of Fig. 6.

Fig. 6 is an elevation of a portion of the feed or storage conduit.

Fig. 7 is an enlarged vertical section through the improved pressure-limit valve.

Fig. 8 is a transverse vertical section through this limit valve, the view being taken substantially on the line 8—8 of Fig. 7.

Referring first to the general assembly shown in Fig. 1, the improved heating system comprises the main source of high pressure steam A which delivers steam through suitable valve connections adapted to reduce the pressure of the steam to the main regulator B which supplies steam to the radiator C through the thermostatically controlled inlet valve D and the feed and storage connections indicated generally at E. The inlet valve D may be controlled by the thermostat F.

The steam regulator B is controlled by the pressure-limit switch G when the storage conduit E is being filled with steam, and is controlled by steam and condensate returned from the radiator through return main H when operating as a vapor system. All condensate is drained out through the drip connection indicated at J.

The car structure indicated in Fig. 1 comprises the floor 1, outer walls 2, and vertical partitions 3 adapted to separate the several compartments or spaces 4. The conduit 5 extends throughout the length of the upper portion of the car, the heating radiator C being mounted in this conduit, as well as the heat-transfer device K of a cooling system, not otherwise disclosed herein. The blower indicated at L and also positioned in the conduit 5 draws in air through the fresh air inlet opening 6, and the returned air inlet opening 7 (these inlets being controlled by suitable valves, not here shown in detail) and forces this air through the conduit 5 in contact with the heating regulator C (or alternatively with the cooling device K), this air being discharged through the several grilles 8 into the compartments 4 of the car. The thermostat F which controls the inlet valve D of the radiator C is preferably located at some suitable position in conduit 5.

The source of steam A, as here shown, is the main train-pipe which extends throughout the length of the train and is supplied with steam from the locomotive. The steam in this pipe will normally be under a rather high pressure, for example 250 pounds. A branch supply pipe 9 leads from train pipe A to the main inlet port of the steam regulator B. In this pipe 9 is located a main cut-off valve 10 which will normally be open, and a reducing valve 11 adapted to materially reduce the pressure of the steam supply to the regulator B, for example to about twenty pounds per square inch.

The steam-regulator B operates similarly to so-called "vapor regulators" already known in the art, except that this regulator is preferably much more delicate in its operation so that the main control valve will not ordinarily be moved abruptly from a fully closed to a fully open position but may be adjusted to selected partially closed positions so as to modulate or reduce the steam flow through the regulator without entirely opening or closing the valve. The improved regulator as partially shown in Fig. 3 is substantially of the type disclosed and claimed more in detail in the copending application of Parks and Peterson, Serial No. 288,104, filed August 3, 1939. For the present purposes this regulator may be briefly described (referring to Figs. 1 and 3) as comprising a casing 12 supported by suitable bracket 13 and formed with an inlet chamber 14 into which steam flows through port 15 from the supply pipe 9. The steam flows from inlet chamber 14 through strainer 16 and passage 17 into the outlet chamber 18 and thence through port 19 into the inlet end portion of pipe 20 (Fig. 1) leading to the pressure-limit valve G. Steam also flows from outlet chamber 18 through a second port similar to 19 but disposed in the opposite wall of the chamber and thence through pipe 21 to the conduit connections E leading to radiator inlet valve D. The movable valve member 23 is guided in cage 24 so as to engage and cooperate with valve seat 25 at the outlet end of passage 17 to cut off the flow of steam from inlet chamber 14 to outlet chamber 18. The spring 26 surrounding valve 23

tends to move valve 23 toward the open position shown in Fig. 3.

A thermostatic member indicated generally at 28 is housed in a chamber 29 formed in a separate casing 30 provided with a plurality of outside radiating ribs 31 so as to expedite the lowering of the temperature around the thermostatic member when steam is no longer admitted to the thermostat chamber 29. Thermostatic member 28 comprises an outer bellows diaphragm 32 and contains a quantity of heat-responsive fluid so that when the thermostatic member is directly exposed to steam it will expand thereby forcing outwardly (to the right Fig. 3) the stem 33 which projects through a sealing member 34 and engages at its outer end the lower arm 35 of a lever adjustably pivoted intermediate its length at 36. The upper arm 37 of this lever is adapted to engage and push inwardly (toward the left Fig. 3) the stem 38 which projects into sealing member 39 and is adapted to engage valve stem 27 and force the valve 23 toward its seat against the opposition of spring 26. When this heating system is functioning like the usual vapor system, this regulator will function like the usual vapor-regulator, that is, after the radiator C has been filled with steam the excess steam will flow back through the return main H and pipe 40 into the inlet port 41 of thermostat chamber 29, the steam acting on the thermostatic member 28 to expand this member and thereby close or partially close the valve 23. In this present improved system steam may also flow from chamber 18 of the vapor-regulator B through pipe 20 to the pressure-limit switch G and thence through pipe 42, Y-connection 43 and pipe 40 into the thermostatic chamber 29 so as to actuate the thermostatic bellows 32. In either case, all condensate flowing into the thermostatic chamber 29 flows out through a port opposite the port 41 and thence through pipe 44 into and through the drip connection J which is preferably protected by outside insulation 45.

The improved pressure-limit valve G (see Figs. 1, 7 and 8) comprises a main casing 46 formed at opposite ends and at one side with three alternative threaded ports 47, 48 and 49 all leading into or from the steam chamber 50 separated by internal web 51 from the upper outlet steam chamber 52. In the example here shown pipe 20 is threaded into the port 48. The other two ports 47 and 49 are closed by suitable plugs 53. Alternatively, this pressure-limit valve might be inserted midway the length of the pipe without interfering with the free flow of steam through this pipe, in which case the two sections of the pipe would be connected in the opposite pair of ports 47 and 48. The pipe 42 leads from the outlet port 54 of the upper steam chamber 52 (Fig. 8) down into the Y-connection 43 and thence into the regulator B (Fig. 1), as already described.

A cage structure 55 is threaded at its lower end 56 in a vertical passage formed in web 51, this cage having a central passage 57 partially closed at its lower end by the perforated strainer 58 and formed at its upper end with valve seat 59. Open passages 60 in the sides of cage 55 permit steam to flow from passage 57 into the upper steam chamber 52 and thence out through pipe 42. The valve 61 which cooperates with valve seat 59 is carried by valve stem 62 slidable through guide-plug 63 mounted in the upper end of cage 55.

The upper end of valve casing 46 is closed by

the solenoid-casing 64 clamped in place by screw-bolts 65 against the interposed gasket 66. The casing 64 encloses the solenoid coil 67 surrounding the guide-tube 68 held in place at its lower end by the nut 69 threaded into the end portion of casing 64. The upper end of valve stem 62 is secured in the solenoid core 70 slideable in guide-tube 68 and pulled up, to open the valve, against the tension of spring 71 when the solenoid is energized. Spring 71 is confined between nut 69 and an outstanding flange 72 at the lower end of core 70. The circuit wires 73 and 74 extending from the respective ends of coil 67 project out through passage 75 into a side extension 16 of casing 64 and connect with the electric terminal member 77 having plugs 78 and 79 projecting downwardly therefrom. The outer electric plug member 80 has sockets to receive the terminals 78 and 79 and is held in place within casing extension 16 by the removable nut 81.

The strength of spring 71 will be so selected or adjusted that the valve 61 will be held down against seat 59 until a predetermined steam pressure, for example ten pounds to the square inch, is built up in the lower steam chamber 50 which pressure will correspond with the pressure in outlet chamber 18 of the steam regulator. As the steam pressure rises above this predetermined pressure the valve 61 will be lifted from its seat against the opposition of spring 71 so as to admit steam into the upper chamber 52 from which chamber this steam will flow through pipes 42, 43 and 46 into the thermostat chamber of the regulator B. Preferably the spring 71 is of such a type that the spring-load will increase rapidly as the spring is compressed, consequently the valve 61 will only be lifted slightly from its seat so as to permit only a restricted flow of steam through the conduit hereinabove described to the thermostat chamber of the regulator. As a consequence the thermostatic bellows will only be slightly expanded so as to only partially close the valve 23 and decrease the flow of steam into chamber 18. The parts will quickly assume a balanced position in which valve 23 is only opened to an extent sufficient to admit enough steam to keep up the desired steam pressure in the outlet chamber 18 of the regulator, and also of course in the conduit connections leading therefrom, including the supply and storage conduit E, hereinafter described.

It will now be apparent that as long as no steam is returning through main H from the radiator to control the regulator E, and as long as solenoid 67 remains deenergized, the valve 23 of the regulator B will remain open admitting steam to the regulator chamber 18 and the feed-pipes 20 and 21 fed therefrom until the pressure in these conduits rises to the predetermined pressure, for example ten pounds, after which the pressure limit valve G will operate automatically to permit a limited flow of steam to the thermostat of the regulator B and thus cut down the steam supply so as to limit the pressure in chamber 18 and the pipes fed therefrom to this predetermined low pressure. When there is an unrestricted outflow of steam through pipe 21 and the feed conduit E and valve D as herein-after explained, this supply pressure will never rise to ten pounds so that the shunt conduit through the limit valve G will remain closed and the regulator B will be entirely under the control of fluids returned from the regulator through return main H. If, at any time, the solenoid 67 is energized (as hereinabove described) the core

70 will be drawn upwardly and valve 61 will be continuously open. In that event there will be a small continuous flow of steam through this shunt conduit so as to maintain the regulator B substantially closed and the heating system will be substantially inoperative.

The improved radiator-inlet valve D will now be described, referring more particularly to Figs. 1 and 4. The main casing 82 of this valve houses an inlet chamber 83 closed at its lower end by a screw plug 84 and provided with a side inlet port 85 into which is fitted the discharge end of the feed or supply pipe E. A passage 86 leads from chamber 83 into the outlet chamber 87, the movable valve member 88 cooperating with valve seat 89 at the discharge end of passage 86 to cut off the flow of steam through the valve. The outlet pipe 89 leading to radiator C (Fig. 1) connects into the outlet port 90 at one side of outlet chamber 87. The upper end of chamber 87 is closed by the solenoid-casing 91 clamped in place against gasket 92 by the bolts 93. The solenoid coil 94 is mounted within casing 91, and the circuit wires 95 and 96 leading from the respective ends of this coil extend through suitable fittings within the casing extension 97, all substantially the same as already described in connection with the pressure limit switch of Fig. 7. The valve 88 is carried at the lower end of valve stem 98 secured at its upper end 99 in the lower end of core 100 which is drawn up into the solenoid through guide-tube 101 when the solenoid coil 94 is energized. The compression spring 102 confined between the screw plug 103 at the lower end of the solenoid assembly, and the collar 104 at the lower end of core 100 functions to close the valve 88 against its seat 89 when the solenoid is deenergized. While this valve will normally be controlled by the spring and solenoid as just described, the valve may also be manually operated by means comprising the disc 105 mounted within chamber 87 on shaft 106 provided outside the valve casing with a handle 107 (Fig. 1). Disc 105 is provided with an arcuate slot 108 into which projects the flange 109 at the lower end of the core assembly. Disc 105 is provided at the side opposite recess 108 with three notches or recesses 110, 111 and 112 into one of which projects the locking pin 113 slideable in the guide bearing 114 and pushed inwardly by the spring 115 confined within plug 116. When disc 105 is in the central position shown in Fig. 4, the valve assembly is operated by the spring and solenoid, the flange 109 reciprocating freely within arcuate slot 108. If the disc 105 is manually rotated in a clockwise direction (Fig. 4) until locking pin 113 has snapped over into notch 112, the shoulder 117 at one end of slot 108 will engage the flange 109 and lift the core and valve assembly so as to open the valve against the resistance of spring 102 and lock the parts in this position. On the other hand, if the disc 105 is rotated in the counter-clockwise direction the shoulder 118 at the other end of slot 108 will engage the flange 109 and lock the valve in closed position. This valve is also disclosed and claimed in the copending application of Parks and Peterson, Serial No. 335,719, filed May 17, 1940.

Reference will now be made to Fig. 2 which shows by way of a wiring diagram a suitable electrical apparatus for thermostatically controlling the valve D. The thermostat F is of the "cycling" type, that is it is provided with an auxiliary source of heat 119 which is energized

at such times as to quickly re-close the thermostat switch after it has been opened by a drop in temperature in the space enclosing the thermostat, after which the auxiliary heating coil 119 is immediately de-energized so as to permit the thermostat switch to again open. The mercury-tube thermostat comprises a mercury column 120 which will always be in engagement with a lower fixed contact 121 and which will engage an upper contact 122 at some predetermined higher temperature.

The relay-coil 123 is normally energized through the following circuit: From power main 124 through wire 125, resistance 126, relay terminal 127, relay coil 123, relay terminal 128, 15 resistance 129, and wire 130 to the other power main 131. When the relay coil 123 is thus energized, it will draw up the core 132 so as to close the pair of switches 133 and 134. The closing of switch 133 will function to open the valve D by energizing the solenoid coil 94 through the following circuit: From power main 124 through wires 125 and 135, switch 133, wire 95, coil 94, and wire 96 to the other power main 131. This will draw in the core 100 and open the valve 88 against the resistance of spring 102. Since steam is now being admitted to the radiator C, the air forced through conduit 5 by blower L will be heated and the thermostat F would eventually respond by raising the mercury column 120 into engagement with the upper fixed contact 122. However, this action of the thermostat will be expedited because the auxiliary heating coil 119 will, simultaneously with the opening of valve 88, be energized through the following circuit: From main 124 through wire 136, heating coil 119, wire 137, resistance 138, wire 139, switch 134, and wire 140 to the other power main 131. The auxiliary heat from coil 119 will cause the mercury column 120 to quickly rise into engagement with the upper thermostat contact 122 thus closing a circuit deenergizing the relay as follows: From one relay terminal 127 through wire 141, thermostat contact 121, mercury column 120, thermostat contact 122, and wire 142 to the other relay terminal 128. Since the relay is now deenergized, the core 132 and the switch contacts carried thereby will drop to the position shown in Fig. 2 thus opening the switches 133 and 134. The opening of switch 133 will deenergize the solenoid 94 and permit spring 102 to close the valve 88 thus cutting off the further flow of steam to the radiator C. At the same time the opening of switch 134 will deenergize the heating coil 119 so that the temperature of the air in conduit 5 (which we assume is not yet sufficiently heated) will cause the mercury column 120 to drop thus again opening the shunt circuit and permitting the energization of the relay to again close the switches 133 and 134. This cycling action will repeat itself until the desired temperature is reached in the air stream, the radiator C being repeatedly filled with bursts of steam but the radiator being filled at less frequent intervals as the desired temperature is approached.

The successful operation of such a heating system necessitates the prompt filling of radiator C when valve D is opened since the valve remains open for only a short period of time. In order 70 to accomplish this quick filling of the radiator, the large capacity inlet conduit E is provided cooperating with the pressure-limit valve G. Since the steam regulator B will usually be positioned beneath the car whereas the radiator C 75

is positioned in the overhead conduit 5, the pipe conduit E will usually be of considerable capacity, but this capacity may be increased by inserting a tank 143 somewhere between the ends of conduit E. Steam flows from the supply chamber 18 of the vapor-regulator B through pipe 21, water-seal M (the function of which will be hereinafter described) and the several sections of supply conduit E including tank 143 up to the inlet valve D. Preferably all portions of the supply conduit E will be suitably insulated so that there will be little condensation and little loss of steam from this portion of the system. Assuming now that the valve D is closed and that there is no further return of steam from the radiator through return main H, the regulator valve 23 will open so as to admit steam from the source A into supply chamber 18 and thence through pipe 21 and water-seal M into the supply conduit E. Steam will simultaneously flow through pipe 20 into the inlet chamber 50 of the pressure-limit valve G. This flow of steam will continue until the inlet conduit E has been completely filled with steam at a predetermined pressure, for example ten pounds. When this predetermined pressure is reached, the pressure-limit valve G will open so as to permit a limited flow of steam through pipe 42 back to the thermostat chamber 29 of the regulator, whereupon the thermostat 28 will function to partially close valve 23. Thereafter there will be just sufficient flow of steam into the storage conduit E to keep this conduit system filled with steam at the desired pressure.

The instant valve D is opened, by the "cycling" system hereinabove described, the supply of steam stored in conduit system E under the adequate pressure hereinabove referred to will rapidly flow into and fill the radiator C. Of course, the pressure in the supply conduit system will drop as soon as this stored volume of steam has flowed into the radiator, and valve G will completely close so as to cut off further flow of steam from this control valve into the thermostat chamber of regulator B. As a consequence the regulator valve 23 will remain completely open to permit additional flow of steam into the supply conduit E but as soon as radiator C has been filled with steam and steam has returned through pipe H to the thermostat chamber of the regulator, the valve E of the regulator B will be partially closed and thereafter the system will operate at substantially atmospheric pressure as in the usual vapor-heating system. As soon as valve D has again closed, by the action of the cycling thermostat F, the outflow of excess steam through return conduit H will cease and valve 23 of the regulator will remain open until the conduit system E is again stored with steam at the predetermined ten pound pressure after which limit switch G will again function to permit sufficient steam to flow back to the thermostat chamber of the regulator B to throttle the main inlet valve 23. The above described cycle of events will then repeat itself. It will be noted that there will always be sufficient steam stored up in the conduit system E to instantly fill the radiator C when valve D is opened.

Referring now again to Fig. 2, at N is indicated a main control switch comprising a lever 144 movable to three different positions in one of which the heating system is operative, in another the cooling system, and in a third intermediate position marked "off" the blower L will be oper-

ative for ventilation purposes only. It will be understood that this switch is considerably simplified in the present showing and will usually comprise additional contacts for effecting different degrees of heating or cooling. When the contact 144 is in the central "off" position shown in Fig. 2, a circuit energizing the solenoid of pressure-limit switch G will be completed as follows: From main 124 through wire 73, solenoid coil 67 of switch G, wire 74, cooling contact 145 of switch N, wire 146, off contact 147, movable switch contact 144, and wire 148 to the other power main 131. It will be obvious that the same circuit will be closed when movable contact 144 is moved into engagement with the cooling contact 145. In either case the solenoid 67 of the switch G will be energized so as to hold the valve 68 open continuously and steam will flow through the shunt circuit from regulator B through valve G back to the thermostat chamber of regulator B and the regulator valve 23 will be held closed except for just sufficient steam flow through this shunt piping to keep the thermostat 28 expanded. At such times there can be no flow of steam through the heating system comprising supply and storage pipe E, radiator C and return main H. It will be noted that when movable contact 144 of valve N is moved over into engagement with the heating contact 149, the circuit just described for energizing the solenoid of valve G cannot be closed and valve D will operate entirely under the control of the spring 71, as originally described.

Referring now to Figs. 1, 5 and 6, the water-seal member M comprises a main casting 150 enclosing a steam chamber 151 having aligned ports 152 and 153 in opposite sides thereof into which are fitted respectively the outlet end of supply pipe 21 leading from the regulator B, and a closure plug 154. A depressed central portion 155 of the casting 150, closed at the bottom by removable plug 156, serves to hold an accumulated pool of condensate 157. A cup-shaped web 158 open at its lower end 159 below the level of pool 157, projects downwardly from the upper portion of casting 150 within the steam chamber 151, this web enclosing a central outlet chamber 160 having an upper outlet port 161 into which the lower end of conduit E is secured. A small vacuum-breaking vent 162 is formed in one side wall of web 158 above the water level of the pool and connecting the inner and outer steam chambers 151 and 160. The function of this water-seal M is to prevent undesired heating and the retention of steam in the conduit E when the valve D is closed for any considerable length of time, for example when the heating system is not in operation. While the heating system is operating, that is the valve D is being opened and closed at frequent intervals by the cycling thermostat F, then the water-seal member M will have no substantial effect on the flow of steam as hereinabove first described. However, if the valve D remains closed, the steam in conduit E will eventually condense and the water from the water-seal member augmented by the condensate formed in conduit E will be sucked up to form a water column in the lower portion of conduit E. The additional small inflow of steam through vent opening 162 will immediately be condensed in this water column. When the car is out of service and there is no longer any steam obtained from the source A, the vent 162 will act as a vacuum breaker to permit the trapped condensate to flow out of the conduit E thus avoiding freezing in the exposed portion of this piping. This wa-

ter-seal mechanism is not claimed herein, but is disclosed and claimed in the copending application of Parks and Stenzel, Serial No. 335,720, filed of even date herewith.

It will now be understood that this improved heating system functions much the same as an ordinary vapor-heating system after the radiator C has once been filled with steam. The principal improvement resides in adding means for storing up a sufficient quantity of steam, under sufficient pressure, to almost instantly fill the radiator with steam once the radiator inlet valve is opened. Thereafter the system operates as a vapor-system until the inlet valve is again closed. In a cycling system of the type herein disclosed it is essential that the radiator be completely filled with steam, as rapidly as possible, so as to avoid stratification or unequal heating of the air stream flowing in contact with the radiator, and it is also necessary to fill the radiator quickly since the "on" period lasts for only a short time. That is, the inlet valve is opened and closed at frequent intervals so that the steam flow does not continually persist for any great length of time and only "bursts" of steam are admitted to the radiator. It is essential that each of these bursts be of sufficient volume and under sufficient pressure to substantially fill the radiator. Thereafter the steam flow does not need to be so rapid and can be under considerably lower pressure, in order to replenish the steam as it is condensed.

Many railway air conditioning systems now in use employ a thermostat in the air delivery duct adapted when the temperature falls to about 60° Fahrenheit to shut off the blower fan, with the assumption that this will only take place when the car is taken out of service. Sometimes, however, due to the slow feeding of steam to the radiators, this thermostat will function to stop the blower fan even while the car is still in service and the heating system is intended to be in operation. This ill-timed stopping of the blower fan is even more apt to take place when a "cycling" system is used which requires frequent re-filling of the radiator. The present improved system, which acts to almost instantly fill the radiator as soon as the inlet valve is opened, effectively avoids this failure of the blower-fan.

In brief, this novel heating system starts off as a pressure system, and then, after the pressure disappears, acts as an ordinary vapor-system. The system is thus provided with a fast-feeding radiator that works effectively in conjunction with a fast-acting thermostat so as to insure a completely filled radiator at all times that this condition is desired.

I claim:

1. In a steam heating system, a radiator, an inlet valve for the radiator, thermostatic means responsive to temperature changes in the space heated for alternately opening and closing said valve at short intervals until a predetermined temperature is reached, a source of high pressure steam, a regulator means receiving steam from the source, and conduit connections between the regulator means and inlet valve having a capacity sufficient to store enough steam to rapidly fill the radiator immediately the valve is opened, said regulator means functioning to fill these conduit connections with steam under a low but super-atmospheric pressure while the inlet valve is closed, and functioning to keep the radiator full of steam while the valve is open.
2. In a steam heating system, a radiator, an

inlet valve for the radiator, thermostatic means responsive to temperature changes in the space heated for alternately opening and closing said valve at short intervals until a predetermined temperature is reached, a source of high pressure steam, a regulator means receiving steam from the source, and conduit connections between the regulator means and inlet valve having a capacity sufficient to store enough steam to rapidly fill the radiator immediately the valve is opened, said regulator means functioning to fill these conduit connections with steam under a low but super-atmospheric pressure while the inlet valve is closed, and functioning to keep the radiator full of steam at atmospheric pressure while the valve is open.

3. In a steam heating system, a source of steam under relatively high pressure, a regulator comprising a supply chamber, a valve controlling the flow of steam from the source to the supply-chamber, a thermostat chamber, a thermostat in the chamber, and connections for moving the valve toward open or closed positions as the thermostat contracts or expands respectively in the presence of steam, and a pair of separate conduit systems for conducting steam between the supply chamber and the thermostat chamber, one system comprising, in order, a steam storage conduit having a capacity sufficient to hold enough steam to quickly fill the radiator with steam at atmospheric pressure, a radiator inlet valve, a radiator and a return pipe, and the other system including a valve opening only when the pressure in the supply chamber exceeds a predetermined maximum, and means comprising a cycling thermostat responsive to temperature changes in the space heated for opening and closing the radiator inlet valve at frequent intervals until a predetermined temperature is reached.

4. In a pressure-starting vapor heating system, a source of steam, a regulator comprising a supply chamber, a valve for controlling the flow of steam from the source to the supply chamber, a thermostat chamber, a thermostatic member in this chamber adapted to move the valve toward open or closed positions, a radiator, an inlet valve at said radiator, means for alternately opening and closing said inlet valve at short intervals in accordance with the heat requirement in the space heated by the radiator until a predetermined space temperature is reached, a supply conduit between the supply chamber of the regulator and the inlet valve, said conduit having a capacity sufficient to hold enough steam under a predetermined super-atmospheric pressure to rapidly fill the radiator immediately after the inlet valve is opened, a return pipe leading from the radiator to the thermostat chamber, a conduit leading directly from the supply chamber of the regulator to the thermostatic chamber, and a limiting valve in this conduit which opens under the predetermined pressure.

5. In a pressure-starting vapor heating system, a source of steam, a regulator comprising a supply chamber, a valve for controlling the flow of steam from the source to the supply chamber, a thermostat chamber, a thermostatic member in this chamber adapted to move the valve toward open or closed positions, a radiator, an inlet valve at said radiator, means for alternately opening and closing said inlet valve at short intervals in accordance with the heat requirement in the space heated by the radiator, a supply conduit including a reserve steam supply tank be-

tween the supply chamber of the regulator and the inlet valve, said conduit having a capacity sufficient to hold enough steam under a predetermined super-atmospheric pressure to rapidly fill the radiator immediately after the inlet valve is opened, a return pipe leading from the radiator to the thermostat chamber, a conduit leading directly from the supply chamber of the regulator to the thermostatic chamber, and a limiting valve in this conduit which opens under the predetermined pressure.

6. In a pressure-starting vapor heating system, a source of steam, a regulator comprising a supply chamber, a valve for controlling the flow of steam from the source to the supply chamber, a thermostat chamber, a thermostatic member in this chamber adapted to move the valve toward open or closed positions, a radiator, an inlet valve at said radiator, means including a cycling thermostat for alternately opening and closing said inlet valve to intermittently fill the radiator with steam in accordance with the heat requirement in the space heated by the radiator until a predetermined space temperature is reached, a supply conduit between the supply chamber of the regulator and the inlet valve, said conduit having a capacity sufficient to hold enough steam under a predetermined pressure to rapidly fill the radiator immediately after the inlet valve is opened, a return pipe leading from the radiator to the thermostat chamber, a conduit leading directly from the supply chamber of the regulator to the thermostatic chamber, and a limiting valve in this conduit which opens under the predetermined pressure.

7. In a pressure-starting vapor heating system, a source of steam, a regulator comprising a supply chamber, a valve for controlling the flow of steam from the source to the supply chamber, a thermostat chamber, a thermostatic member in this chamber adapted to move the valve toward open or closed positions, a radiator, an inlet valve at said radiator, means for alternately opening and closing said inlet valve at short intervals in accordance with the heat requirement in the space heated by the radiator, a supply conduit between the supply chamber of the regulator and the inlet valve, said conduit having a capacity sufficient to hold enough steam under a predetermined pressure to rapidly fill the radiator immediately after the inlet valve is opened, a return pipe leading from the radiator to the thermostat chamber, a conduit leading directly from the supply chamber of the regulator to the thermostatic chamber, and a limiting valve in this conduit which opens under the predetermined pressure.

8. In a pressure-starting vapor heating system, a source of steam, a regulator comprising a supply chamber, a valve for controlling the flow of steam from the source to the supply chamber, a thermostat chamber, a thermostatic member in this chamber adapted to move the valve toward open or closed positions, a radiator, an inlet valve at said radiator, means for alternately opening and closing said inlet valve at short intervals in accordance with the heat requirement in the space heated by the radiator, a supply conduit between the supply chamber of the regulator and the inlet valve, said conduit having a capacity sufficient to hold enough steam under a predetermined pressure to rapidly fill the radiator immediately after the inlet valve is opened, a re-

turn pipe leading from the radiator to the thermostat chamber, a conduit leading directly from the supply chamber of the regulator to the thermostatic chamber, a limiting valve in this conduit which opens under the predetermined pressure, a master control switch, and electrically actuated means for holding said limiting valve open when the switch is adjusted to render the heating system inoperative.

9. In a steam heating system, a conduit, a radiator in this conduit, means for forcing an air stream through the conduit in contact with the radiator, an inlet valve for the radiator, means for opening and closing the inlet valve at frequent intervals until a predetermined air stream temperature is reached, a source of steam, a regulator comprising a supply chamber, a valve controlling the flow of steam from the source to the supply chamber, a thermostat chamber, a thermostatic member in the chamber, and connections for moving the valve toward open or closed positions as the thermostatic member contracts or expands respectively, and a pair of separate conduit systems between the supply chamber and the thermostat chamber, one system comprising, in order, a steam storage conduit located outside the air conduit, said conduit having a capacity sufficient to hold enough steam under a predetermined super-atmospheric pressure to rapidly fill the radiator immediately after the inlet valve is opened, the inlet valve and radiator, and a return pipe, and the other system including

5 a valve opening only when the pressure in the supply chamber exceeds a predetermined maximum.

10. In a steam heating system, a conduit, a radiator in this conduit, means for forcing an air stream through the conduit in contact with the radiator, an inlet valve for the radiator, means comprising a thermostat in the path of the heated air stream and means for artificially heating the thermostat for opening and closing the inlet valve at frequent intervals until a predetermined air stream temperature is reached, a source of steam, a regulator comprising a supply chamber, a valve controlling the flow of steam from the source to the supply chamber, a thermostat chamber, a thermostatic member in the chamber, and connections for moving the valve toward open or closed positions as the thermostatic member contracts or expands respectively, and a pair of separate conduit systems between the supply chamber and the thermostat chamber, one system comprising, in order, a steam storage conduit located outside the air-conduit, said conduit having a capacity sufficient to hold enough steam under a predetermined super-atmospheric pressure to rapidly fill the radiator immediately after the inlet valve is opened, the inlet valve and radiator, and a return pipe, and the other system including a valve opening only when the pressure in the supply chamber exceeds a predetermined maximum.

PAUL B. PARKS.

CERTIFICATE OF CORRECTION.

Patent No. 2,274,736.

March 3, 1942.

PAUL B. PARKS.

It is hereby certified that error appears in the printed specification of the above numbered patent requiring correction as follows: Page 6, second column, line 4, claim 5, before "pressure" strike out "super-atmospheric" and insert the same after "predetermined" in line 28, claim 6; and that the said Letters Patent should be read with this correction therein that the same may conform to the record of the case in the Patent Office.

Signed and sealed this 28th day of April, A. D. 1942.

Henry Ven Arsdale,
(Seal) Acting Commissioner of Patents.
